BREAK-DOWN MILL

Alexander Paterson, Buffalo, N. Y.

Application August 8, 1933, Serial No. 684,181

12 Claims. (Cl. 80—55)

This invention relates to an improved break-down mill for use in sheet and tin plate rolling and more particularly the invention involves improvements in the mill disclosed and claimed in my Patent No. 1,804,111, granted May 5, 1931.

The mill covered by my said patent includes one or more units which are characterized by opposed integral housings, each having windows for a multiple arrangement of roll sets together with means intermediate the sets and successively co-operating with each of them for feeding and guiding the piece to be rolled. The piece is caused to move continuously forward through the successive roll passes, the means intermediate the reducing passes engaging the piece before it leaves the pass behind and directing it to the pass in front and remaining in engagement with it until it has entered the rolls of the pass to which it is directed. In this way a "square" or true feed of the piece is assured as is also the automatic passage of the piece through the series of rolls sets, the last set of rolls reducing the piece to a predetermined cross-section. The mill has the advantage that the reduction of the piece is accomplished more rapidly than has heretofore been possible, the close proximity of the various sets of rolls of the reducing passes assuring passage of the piece through the mill at such a rate as to eliminate, to a substantial degree, heat losses. The capacity of the mill is, therefore, high. The multiple window housings not only enable a closer arrangement of the sets of reducing rolls than has heretofore been possible but they also have greater strength for the support of the rolls and for taking up the stresses that may be developed.

In the various illustrated embodiments of the present invention the mill is shown as comprising a single unit. It is to be understood, however, that while a single unit may be adequate, (assuming the nature of the work permits suitable reduction in the number of passes thus provided) for ordinary use with pieces commencing in size at the sheet bar stage, two units will be preferred and in such case suitable feeding and guiding means may be provided intermediate and in co-operation with the units as disclosed in my said Patent No. 1,804,111.

One object of the invention is to provide for facility in removing and replacing the rolls of the mill without the necessity of disturbing the housings thereof.

A further object is a mill of the type generally described in which provision is made for accommodating rolls of various diameters, where-

by to enable conditioning of the mill to meet different rolling requirements.

A still further object is to provide a mill which is convertible to accommodate different roll combinations.

Embodiments of the invention are illustrated in the accompanying drawings, in which:

Figure 1 is a view in elevation of a mill unit in which features of the invention are incorporated.

Figure 2 is a front view of the mill part in section and part in elevation.

Figure 3 is a perspective view of a roll frame.

Figure 4 is a view similar to Figure 1 of a modified form of mill unit.

Figure 4a is a section through one of the wedges by which the roll frame is secured in its housing, the said section being taken along line 4a—4a of Figure 1.

Figure 5 is a view similar to Figure 4 of a further modified form of mill unit.

Figure 6 is a perspective view of the roll frame employed in connection with the embodiment shown in Figure 5.

The mill unit, as illustrated in Figure 1, includes two sets of three-high rolls which are mounted in housings 10 arranged in opposed relation in the usual manner. Each housing is of integral construction and is formed with a centrally located opening 11. The sets of rolls are 30 similar to one another and each consists of an upper roll 12, an intermediate roll 13 and a lower roll 14. As shown, the upper roll 12 and the intermediate roll 13 are employed to roll the piece while the lower roll reinforces the intermediate roll 13. The rolls may be driven in any suitable manner. The piece is directed from the working pass of one set of rolls to the working pass of the succeeding set of rolls by sheet feeding and guiding means arranged between the 40 sets of rolls and consisting of a feed roll 15 and a weighting roll 16, the feed roll being driven in any suitable manner. In its travel through the passes of the unit the piece is engaged by the feed and weighting rolls 15 and 16 respectively, just before it is discharged from the first set of working rolls and is fed forward until it enters the second set of working rolls, the said feed and weighting rolls maintaining engagement with the piece until it is engaged by the second set of 50 working rolls, whereby to assure a "square" or true feed of the piece. The rolls 15 and 16 are preferably employed in connection with a guide table or plate 17 which bridges the space between the passes of the two sets of rolls.

In accordance with the invention means is provided for facilitating removal and replacement of the rolls of the unit. To this end a frame 18 is arranged in each of the openings 11. The frame is supported upon a centrally located rib 19 and overlies shoulders 20, the said rib and shoulders being located in substantially the same horizontal plane. A division bar 21 of the said frame co-operates with side bars 22 and 23 there-of to provide windows 24 and 25 in which the necks of the working rolls 12 and 13 are fitted, the rib 19 dividing the lower part of the opening 11 into supplemental windows 26 and 26a for the necks of the backing rolls 14. Brasses 27 for the upper rolls and 28 and 28a for the intermediate rolls are carried by the frame 18 while brasses 29 for the lower rolls are carried directly by the housings. The division bars 21 of the frames 18 may, as illustrated, be formed with opposed openings 21a to accommodate the shafts of the feed and weighting rolls 15 and 16 respectively. The said bars may also be formed with shoulders 21b for the support of the guide table or plate 17, the latter being carried by a bar 17a which is positioned in grooves 21c formed in the said shoulders. The top bar 30 of the frame is formed with openings 31 through which the adjusting screws 19 extend, the said screws co-operating with conventional bearing blocks 32 which carry brasses 34 for engagement with the necks of the rolls 12. The blocks 32 are mounted for vertical adjustment in guideways 33 which are formed in the division and side bars of the frame.

The frame 18 is removably secured in the opening 11 by elements 35 (Figures 1 and 4a). The latter includes wedge-like shanks 36 which extend between the side walls of the opening 11 and the side bars 22 and 23 of the frame. Preferably the shanks 36 of the elements fit in recesses 10a which are formed in the side walls, the said recesses having inclined bottom walls 10b to compensate for the taper of the shanks. The elements include laterally extending heads 37 and are carried from the housings 10 by bolts 38 which pass through suitable openings formed in said heads. Nuts 39 which are carried by said bolts are adjustable to force the wedge-like shanks of said elements into the space between the frame and the housing, thereby to secure the frame rigidly in the opening 11.

It will be apparent that the frames 18 may be removed from the housings by loosening the nuts 39 and withdrawing the elements 35, it being understood that the adjusting screws 19 are first withdrawn from the openings 31 in the top bars of the frames. Upon removal of one of the frames 18 either or both of the working rolls 12 and 13 may be withdrawn axially through the opening 11 without disturbing the housings 10 and without necessitating the removal of the frame of the companion housing. It is understood, of course, that the removal of the working rolls may be necessary for a number of reasons, for example, it may be desired to recondition the rolls or to replace them with new ones, it being understood that in the latter instance the new rolls may be of the same or different diameters with respect to the original rolls.

The lower rolls 14 serve only to reinforce the intermediate or working rolls 13. As the wear upon these rolls is slight, the necessity for changing them will seldom arise. They may, however, be removed by lifting them and then withdrawing them axially through that part of the opening 11 from which the frame has been removed. In

this connection it is to be understood that in the removal of the various rolls either or both of the frames 18 may be removed. The invention also contemplates the use of a frame in only one of the housings in the event that the characteristics of the rolls are such that they may be removed and replaced in the manner desired by the removal of the frame. Preferably, however, there will be a frame employed in connection with each of the housings.

The intermediate or working rolls 13 wear considerably faster than either of the upper or lower rolls. Means is provided, therefore, whereby these rolls may be removed from the housings without the necessity of disturbing the housings or removing either of the frames 18. To this end the brasses 28 are carried by blocks 40. The latter are secured in any suitable manner in recesses 40a which are formed in the side bars of the frames. When the blocks are removed the recesses thus provided increase the width of the windows 24 and 25 to such an extent that the rolls when lifted and moved laterally with respect to their normal position can be withdrawn axially through the windows, it being understood that in the removal of the rolls in this manner parts of the roll bodies pass through the said recesses. In this connection it will be noted that the shanks of the elements 35 are located directly behind the brasses of the various rolls. Hence any lateral thrusts of the rolls will be transmitted through the brasses and elements directly to the housings.

From the foregoing it will be noted that provision is made for removing and replacing the various rolls of the mill without the necessity of disturbing the housings. Such removal and replacement can be effected conveniently and with facility. In the event that such replacement or removal involves only the intermediate or lower working rolls 13 this can be done not only without disturbing the housings 10 but also without necessitating the removal of either of the frames 18. It is to be understood that although the lower rolls 14 are referred to as backing rolls, the said rolls may, if desired, be availed of in connection with the intermediate rolls to provide a reducing pass. It is to be understood further that the invention contemplates the use of a removable frame in only one of the housings if this is desired, it being apparent that the withdrawal of the various rolls in the manner described can be effected by removing a single frame. When a single frame is employed the rolls of course will be withdrawn through the opening in the housing occupied by the frame.

Means is provided whereby the mill unit illustrated in Figure 1 may be converted into a two-high unit. A unit of this type is illustrated in Figure 4. It includes two sets of two-high rolls which are mounted in housings 41 arranged in opposed relation. The said housings are similar to the housings illustrated in Figure 1 and each is formed with a centrally located opening 42. Each of the sets of rolls includes an upper working roll 43 and a lower working roll 44. A frame 45 which is located in the opening 42 is formed with a division bar 46, the latter co-operating with the side bars 47 and 48 of the frame to provide windows 49 and 50. Brasses 51 for the upper rolls are carried by the frames 45. The lower working rolls 44 are fitted in supplemental windows 52 and 53 which comprise the lower part of the openings 42 and which are formed by ribs 54. The brasses 55 for the lower working rolls are carried directly by the hous- 75

ings. Elements 56 are adapted to secure the frame 45 in the opening 42 as described in connection with the embodiment shown in Figure 1. Adjusting screws 57 pass through openings 58 formed in the top bar 59 of the frame and co-operate with bearing blocks 60 to control the pass provided by the working rolls, the said bearing blocks carrying brasses 61 which engage the necks of the upper rolls. The said blocks are mounted in suitable guideways 62 which are formed in the said frames and which are adapted to permit vertical movement of the blocks as determined by the adjusting screws 57. In this embodiment the bearing blocks 60 for the upper rolls, as distinguished from those shown in Figure 1, are elongated, the said blocks serving to adapt the housings to two-high sets of rolls. It will be apparent, therefore, that by the use of different frames and bearing blocks the same housings may be adapted to accommodate different roll combinations. It will be noted that in this embodiment a sheet feed mechanism is not employed in connection with the working rolls, it being within the contemplation of the invention that when circumstances permit the piece may be fed by the first set of rolls directly to the succeeding set of rolls, the piece in this instance being engaged by the former until it enters the latter.

In the embodiment shown in Figure 5 the mill which is illustrated is generally similar to the mill illustrated in Figure 1. It includes two sets of three-high rolls which are mounted in housings 63 arranged in opposed relation in the usual manner. Each housing is of integral construction and is formed with a centrally located opening 64. The sets of rolls are similar to one another and each consists of an upper roll 65, an intermediate roll 66 and a lower roll 67. As described in connection with Figure 1 the upper rolls 65 and the intermediate rolls 66 are employed to roll the piece while the lower rolls 67 reinforce the intermediate rolls 66. It is to be understood, of course, that the rolls 67 are, if desired, available for cooperation with the rolls 66 to provide reducing passes. The windows 68 and 69 for the upper and intermediate rolls 65 and 66 respectively are provided by a frame 70 which is arranged in the opening 64. The said frame includes upper and lower bars 71 and 72 respectively and a division bar 73. The lower part of the opening 64 is divided by a rib 74 into supplemental windows 75 and 76 for the lower rolls 67. The frame 70 is supported upon the rib 74 and it is removably secured in the opening 64 by elements 77. The latter are similar to and function in substantially the same manner as the elements 35 shown in Figure 1. In the present embodiment the elements co-operate with the ends of the bars 71 and 72.

Brasses 78, 79 and 80 are employed in connection with each of the upper rolls 65, the brasses 78 being carried directly by the housings 63 while the brasses 79 are carried by the division bars 73. The brasses 80 are carried by bearing blocks 81 which co-operate with the adjusting screws 82 to control the degree of reduction, the said screws passing through openings 71a formed in the top bars 71 of the frames. Brasses 83 and 84 for the intermediate rolls 66 are carried by the housings and division bars respectively while brasses 75a for the lower rolls are carried by the housings. In this embodiment the brasses 83 are carried by blocks 85. The latter are removably secured in any suitable manner in re-

cesses 86 which are formed in the housings 63 adjacent the intermediate rolls 66. By removing the said blocks the windows are increased in width at these points to such an extent that the said rolls may be withdrawn axially from the 5 housings, as described in connection with Figure 1, without the necessity of disturbing the housings or the frame. In order to enable removal of the upper and lower rolls 65 and 67 respectively either or both of the frames 70 may be 10 first removed as described in connection with Figure 1.

From the foregoing it will be apparent that mill units constructed in accordance with the invention have the advantage that the rolls may 15 be removed, replaced or interchanged as occasion may require without the necessity of disturbing the housings. A further advantage obtained is that the housings are adaptable to accommodate different roll combinations, it being 20 understood in this connection that the frames which are employed for this purpose may be of various forms, those illustrated being by way of example only.

I claim as my invention:

1. A breakdown mill including an integral housing formed with a plurality of windows, a companion housing formed with an opening, a frame located in said opening, said frame having a central bar which divides said opening into 30 a plurality of windows which register with the windows of said first mentioned housing, a set of rolls fitted in each pair of registering windows, and means carried by said central bar for feeding a sheet metal section from one set of said rolls 35 to a companion set, said frame being removable to enable removal of said rolls without disturbing said housings.

2. A breakdown mill including an integral housing formed with a plurality of windows, a 40 companion housing formed with an opening, a frame arranged in said opening, said frame having a central bar which divides said opening into a plurality of windows which register with the windows of said first mentioned housing, a set 45 of rolls fitted in each pair of registering windows, brasses for said rolls carried by said central bar, means carried by said central bar for feeding a sheet metal section from one set of rolls to a companion set, and means for removably securing said frame in said opening, whereby to enable removal of said rolls without disturbing said 50 housings.

3. A breakdown mill including an integral housing formed with a plurality of windows, a 55 companion housing formed with an opening, a frame arranged in said opening, said frame having a central bar which divides said opening into a plurality of windows which register with the windows of said first mentioned housing, a set 60 of rolls fitted in each pair of registering windows, said rolls being of a diameter greater than the width of said windows, means for removably securing said frame in said opening, whereby to enable removal of said sets of rolls, and means 65 carried by said frame which is removable to increase the width of one of said windows to permit withdrawal of one of said rolls axially through said window without disturbing said frame or said housings.

4. A breakdown mill including an integral housing formed with a plurality of windows, a companion housing formed with an opening, a frame arranged in said opening, said frame including side bars and a central bar, the latter dividing 75

- the frame into a plurality of windows which register with the windows of said first mentioned housing, a set of rolls fitted in each pair of registering windows, means carried by said 5 central bar for feeding a sheet metal section from one set of said rolls to a companion set, and wedges co-operating with the said side bars for removably securing said frame in said opening, whereby said rolls can be removed without disturbing said housings.
5. A breakdown mill including an integral housing formed with a plurality of windows, a companion housing formed with an opening, a frame arranged in said opening, said frame including 10 a top bar and a central bar, the latter dividing said opening into a plurality of windows which register with the windows of said first mentioned housing, a set of rolls fitted in each pair of registering windows, means carried by said central 15 bar for feeding a sheet metal section from one set of said rolls to a companion set, means for removably securing said frame in said opening, whereby to enable removal of said sets of rolls without disturbing said housings and adjusting 20 screws carried by said housings for controlling the passes provided by said rolls, said top bar being formed with openings through which said screws extend.
6. A breakdown mill including an integral 25 housing formed with a plurality of windows, a companion housing formed with an opening, a frame arranged in said opening, said frame including top and bottom bars and a central connecting bar, the latter dividing said opening into a plurality of windows which register with the windows of said first mentioned housing, rolls fitted in each pair of registering windows, means for removably securing said frame in said opening, whereby to enable removal of said rolls without disturbing said housings and co-operating 30 pairs of brasses which engage opposite sides of the necks of said rolls, one of each pair of said brasses being carried by said central bar and the other of said pair being carried by a wall of said 35 housing.
7. A breakdown mill including an integral 40 housing formed with a plurality of windows, a companion housing formed with an opening, a frame arranged in said opening, said frame including top and bottom bars and a central connecting bar, the latter dividing said opening into a plurality of windows which register with the windows of said first mentioned housing, rolls fitted in each pair of registering windows, said 45 rolls being of a diameter greater than the width of said windows, means for removably securing said frame in said opening, whereby to enable removal of several of said rolls without disturbing said housings and a member carried by one of said 50 housings and which is removable to increase the width of a window, whereby to enable withdrawal of one of said rolls axially through said window without disturbing said frame or said housings.
8. A breakdown mill including a housing 55 formed to provide a plurality of windows, a companion housing formed with an opening, a frame in said opening which divides it into a plurality of windows which are located opposite the windows of said first mentioned housing, a plurality 60 of pairs of rolls, each of said windows accommodating the necks of a pair of said rolls, means for removably securing said frame in said companion housing, whereby it may be removed to permit removal of several of said rolls without disturbing said housings and bearings which engage the 65 70 75
- sides only of said roll necks, the windows provided by said frame being unobstructed between said bearings, one of said bearings being removably secured in position, whereby it may be removed to enable removal of one of said rolls without the necessity of removing said frame.
9. A breakdown mill including a housing formed to provide a plurality of windows, a companion housing formed with an opening, a frame in said opening which divides it into a plurality of windows which are located opposite the windows of said first mentioned housing, a plurality of pairs of rolls, each of said windows accommodating the necks of a pair of said rolls, means for removably securing said frame in said companion housing, whereby it may be removed to permit removal of several of said rolls without disturbing said housings and bearings carried by said frame which engage the sides only of said roll necks, the windows provided by said frame being unobstructed between said bearings, one of said bearings being removably secured in said frame, whereby it may be removed to enable removal of one of said rolls without the necessity of removing said frame.
10. A breakdown mill including a housing formed to provide a plurality of windows, a companion housing formed with an opening, a frame in said opening, said frame including side bars and a central bar which divide said opening into a plurality of windows which are located opposite the windows of said first mentioned housing, a plurality of pairs of rolls, each of said windows accommodating the necks of a pair of said rolls, means for removably securing said frame in said companion housing, whereby it may be removed to permit removal of several of said rolls without disturbing said housings and bearings carried by said bars which engage the sides only of said roll necks, the windows provided by said frame being unobstructed between said bearings, one of said bearings being removably secured in said frame, whereby it may be removed to enable removal of one of said rolls without the necessity of removing said frame.
11. A breakdown mill including a housing formed to provide a plurality of windows, a companion housing formed with an opening, a frame in said opening, said frame including side bars and a central bar which divide said opening into a plurality of windows which are located opposite the windows of said first mentioned housing, a plurality of pairs of rolls, each of said windows accommodating the necks of a pair of said rolls, means for removably securing said frame in said companion housing, whereby it may be removed to permit removal of several of said rolls without disturbing said housings, bearings carried by said bars which engage the sides only of said roll necks, the windows provided by said frame being unobstructed between said bearings and means for removably securing one of said bearings in said frame, whereby it may be removed to enable removal of one of said rolls without the necessity of removing said frame, said means including a block which fits in a recess formed in one of said frame bars and which is removable to increase the width of the window which accommodates the neck of the said roll.
12. A breakdown mill including a housing formed to provide a plurality of windows, a companion housing formed with an opening, a frame in said opening, said frame including side bars and a central bar which divide said opening into a plurality of windows which are located opposite

the windows of said first mentioned housing, a plurality of pairs of rolls, each of said windows accommodating the necks of a pair of said rolls, means for removably securing said frame in said 5 companion housing, whereby it may be removed to permit removal of several of said rolls without disturbing said housings, bearings carried by said side bars which engage the sides only of said roll necks, the windows provided by said 10 frame being unobstructed between said bearings

and means for removably securing one of said bearings to one of said side bars, whereby it may be removed to enable removal of one of said rolls without removing said frame, said means including a block which fits in a recess formed in 5 one of said side bars and which is removable to increase the width of the window which accommodates the neck of the said roll.

ALEXANDER PATERSON. 10
